UNITED STATES PATENT OFFICE.

EMANUEL OEHRL, OF OMAHA, NEBRASKA.

COMBINATION-TOOL.

968,679.

Specification of Letters Patent. Patented Aug. 30, 1910.

Application filed June 7, 1909. Serial No. 500,547.

To all whom it may concern:

Be it known that I, EMANUEL OEHRL, citizen of the United States, residing at Omaha, in the county of Douglas and State 5 of Nebraska, have invented certain new and useful Improvements in Combination-Tools, of which the following is a specification.

My invention relates to an improved combination tool of general mechanical use as a 10 level, plumb, inclinometer, protractor, bevel, depth gage and centering-square; and the objects of my improvement are, first, to provide such a tool of a greater range of usefulness without increasing the number of 15 parts or adding to the whole size or weight; second to provide a clamping device by which a swinging slideable straight-edge and measuring blade having a single longitudinal groove may be attached at either edge to 20 a stock and the ends reversible in every case; third, to provide an adjustable releasable detent to stop the swing of the blade exactly at right angles to the face of the stock or allow it to pass to any other desired angle; and fourth, to provide a more positive 25 releasable grip to temporarily retain said blade at any desired angle to said stock. I attain these objects, with others of minor importance, by the mechanism illustrated in 30 the accompanying drawing in which—

Figure 1 is a side elevation of the tool arranged as a level for an under surface, for instance: a soffit or ceiling, and as a machinist's centering-square; Fig. 2, is an underside view of Fig. 1; Fig. 3, is a top view of Fig. 1; Fig. 4, is a side elevation as it appears when arranged as a plumb, in which form it is also used as a square or depth gage; Fig. 5, is a side elevation opposite to Fig. 1, the blade swung edgewise 180 degrees to the opposite or under edge of the stock, in which form the long lower edge of the blade may be used to level a top surface or floor and the face or top edge of the stock 45 3 to level an under surface or ceiling; Fig. 6, is a vertical longitudinal central section of the stock 3 in the position shown in Fig. 1, all separable parts removed and the blade 2 indicated by broken lines; Fig. 7, is an under side view of the whole stock in position shown in Fig. 1, all separable parts removed and the lower edge of the blade indicated by broken lines; Fig. 8, an enlarged sectional detail view of the detent 34 and adjacent

parts, in connection with the oscillating 55 quadrantal limb 24, in the position shown in Fig. 4; Fig. 9, a side elevation of the oscillating quadrantal limb and blade-clamp, partly in section to disclose the mechanism of the clamp; Fig. 10, a top view of the detent 34 turned to the position shown in Figs. 4 and 8 to stop the oscillation of the limb and swing of the blade at a predetermined angle to the face of the stock; Fig. 11, an underside view of the detent 34 and its 60 65 pivotal screw or broad headed journal 36, showing the detent turned to the position shown in Figs. 1 and 2 to allow the limb 24 to pass through the notch 40; Fig. 12, is a section on the broken line 12—12, of Fig. 9, 70 disclosing the mechanism of the clamping device to lock the oscillating limb and blade-clamp, and showing the blade-seat or bottom of the fork through the blade-clamp; and, Figs. 13, 14, 15 and 16, are diagrams illustrating respectively the application of the tool in turning a reducing taper, laying out ratchet teeth, gaging the length of a shouldered journal and turning a countersunk head, which are a few of the many ways in 75 80 which the tool may be employed.

Similar numerals refer to similar parts throughout the several views.

The three principal parts of the tool comprise an oblong stock bifurcated at one end 85 and having a longitudinally-grooved working face on one edge and a centering head at the end opposite to said bifurcation, an oscillatory quadrantal graduated limb and integral blade-clamp pivoted between the ends 90 of the forked branches of the stock and a grooved ruling and measuring blade adapted to slide in and be fastened in said blade-clamp. Other smaller coöperative parts are attached and connected as set 95 forth below.

The stock 3 consists substantially of an oblong flat bar one of its edges finished to serve as the working face 1; one end has the V-shaped notch or fork formed by the inwardly inclined edges 9 and 9 to form, in conjunction with the seated blade 2, a common centering-square as shown in Fig. 1. The face edge has the deep cut groove 46 to loosely but closely receive the blade edge-wise as indicated in Fig. 6 and shown in Figs. 1 and 3. The end opposite to the centering notch or head is bifurcated, divided

edgewise and centrally and the ends of the branches bent away from the face edge of the stock to form the supports 4 and 4, through which the pivot or bolt screw 30 is disposed to carry the oscillatory limb 24 and the integral blade-clamp 13. As shown in Figs. 6 and 7 the space between the branches is widened beyond the width of the groove 46 by the curve-edged recesses 6 and 6 on the inside of each branch to receive and let pass the oscillatory limb, the deeper oblique edged recesses 7 and 7 to receive the inner web-part of the blade-clamp 13 and the still wider curved-edged recesses 8 and 8, to receive the ends of the hub 27 of the integral oscillatory limb and blade-clamp.

The limb and clamp are constructed, disposed and pivoted as shown in Figs. 1, 2, 4 and 5 and further illustrated by enlarged 20 details in Figs. 9 and 12.

The hub 27 has its bore shaped to form the taper or countersink 28 at one end. The pivotal screw-bolt or journal 30 has the enlarged threaded head 31 seated tightly in 25 one of the branch-supports 4, and the shank 30 passed plainly through the opposite branch-support and is provided beyond with the threaded end 32 to receive the tail-nut 33. The shank 30 and the threaded head 31 are connected by the integral countersunk head or tapered part 29, fitted to exactly fill the countersunk end 28 of the hub bore. This gives a wedging grip in the hub to lock it against revolving when the 30 tail-nut is turned home. This grip is adjusted and the desired position of the tail-nut when tightened, as shown in Figs. 4 and 5, is attained by turning the screw-head 31.

The blade-clamp 13 is an integral projection 40 from the hub 27 and is bifurcated centrally to receive, seat, and carry the blade 2 edgewise in a plane agreeing with the plane of rotation of the clamp and with the groove 46 in the face of the stock; the blade-seat or 45 bottom of the bifurcation in the clamp and the bottom of the groove 46 in the stock are in alinement on the same tangential line to the hub when the blade is swung to the position shown in Fig. 1 and as indicated in 50 Figs. 6 and 9. The clamp has a central cross-enlargement to form the casing 14 to inclose the clamping bolt 16 axially disposed at the center of and at right angles to the bottom of the fork or blade-seat. This bolt 55 of larger diameter than the width of the bifurcation has the longitudinally reduced portion 17 Fig. 9 lying outside of the blade-seat and space and has at its end the inwardly bent head or lip 18 to engage and 60 slide in the groove 23 in the blade. The opposite end of the bolt 16 is threaded to take the thumb-nut 15 by which the inner edge of the blade is drawn and fastened firmly against its seat in the fork. The coil 65 spring 22 is disposed in the annular cham-

ber 21 in the clamp or bolt casing to press against the bearing face of the thumb-nut and draw the bolt with sufficient force to prevent the blade from sliding out when the bolt is loosened. A cross-pin is disposed centrally through the body of the bolt the ends projecting to form the diametrically oppositely disposed radial lugs 20 and 20; and chambers 19 and 19 are formed in the walls of the casing below the blade-seat to receive said lugs. By slackening the nut sufficiently these lugs may be reversed in the chambers by turning the bolt half-way around thus bringing the reduced portion 17 and the hooked head 18 into the opposite branch or side of the fork; whereby the grooved and plain sides of the blade may be reversed and still retain the same edge of the blade in the seat, or the edges of the blade may be changed in the clamp without reversing the ends of the blade; thereby allowing the mitered end of the blade within the plane of its movement to be applied in all positions and directions relative to the face of the stock.

The oscillatory quadrantal graduated limb 24 is an integral projection from the hub 27 and disposed oppositely to the blade-clamp, to swing through the forked end of the stock. One side bears along its peripheral edge the quadrantal arc 26 divided into degrees from zero to 90, and reversely numbered to read readily from either end and give the complemental angles. The opposite side has the graduated arc scale 25 to set the blade for the exterior angles of different polygons. The stock has on each side two reading or index marks 11 and 12 spaced ninety degrees apart. The index marks 11 and 11 are placed on the beveled rim of the apertures 5 and 5 in the branches of the stock, through which openings the graduations of the limb are read. And the index marks 12 and 12 are placed on the oppositely beveled sides of the detent table or seat 39 adjacent to the periphery of the limb, all as shown in Figs. 1, 4 and 5. With the blade in the position shown in Fig. 4 any degree of angle from zero to ninety degrees, to the position of the blade shown in Fig. 1, is read at the index mark 12; and, any position of the blade between that shown in Fig. 4 and that shown in Fig. 5, covering ninety degrees or the other half of the semicircle, is read at the index 115 mark 11.

An adjustable rotatable detent 34 of discal form is mounted on the shank of the screw or broad-headed journal 35, which has its threaded point driven into the detent table or seat 39. The detent revolves in a plane at right angles to the plane of revolution of the limb; the periphery of the detent extending into the sweep of oscillation of the limb the edge of which 130

strikes the face of the detent to arrest the movement of the limb and stop the blade at right angles to the face of the stock as shown in Figs. 8 and 4 and indicated by broken lines in Fig. 10. The screw has a broad head 36 to supply ample support to the detent and is slotted to take a common screw-driver to make the required adjustments. The detent has the rectangular radial notch 40 in its periphery, adapted to loosely receive the overlapping edge of the limb and allow it to swing through unobstructed as indicated in Fig. 11 and shown in Fig. 1. The striking and seat face of the detent has the annular groove 37 spaced away from the central bore to leave a full length solid hub to support the detent; in this annular groove is seated the coil spring 38 to bear against the seat and retain the detent against the head 36 when the screw is turned in or out to adjust the detent to stop the limb to set the blade at the correct desired or right angle.

In the end of the oblique arm 9 opposite to the face edge of the stock, the notch 10 is cut—as shown in Figs. 2, 5, 6, and 7,—to receive seat and stay the inner edge of the blade in the position shown in Fig. 5. And on the outside of said arm the boss 44 is disposed and bored to receive the adjusting screw 43 to limit the inward swing of the blade and stop and seat it parallel with the face of the stock, turned 180 degrees from the position shown in Fig. 1.

35 A spirit level consisting of the ordinary glass tube is disposed in the cylindrical metal case 42 having ears at its ends to receive the screws 45 and 45 by which it is fastened to the back edge of the stock. The stock is recessed away from the open glass face of the level which is turned permanently toward the stock to avoid breakage. It is obvious that with the range of movement and possible positions of setting the 45 blade this single well protected spirit-level will serve every purpose of leveling plumbing or laying out any incline from the horizontal to the perpendicular.

The outer end 54 of the blade clamp is 50 squared to the blade-seat and beveled on each side for convenient reading of the graduated scales on the blade and when placed as shown in Fig. 4 or as indicated in Fig. 15 serves as a depth gage or to measure a projecting part.

I claim:

1. A combination tool comprising an oblong stock having a face edge, a longitudinal groove throughout said face edge to form a blade-seat, one end of said stock bifurcated in a plane agreeing with said longitudinal groove, a blade-clamp pivoted between the branches of said bifurcation, a blade adapted to be fastened in said clamp 60 to swing therewith and seat in said groove,

and the opposite end of said stock V-shaped to form with the seated edge of the blade a centering-square.

2. A combination tool, comprising an oblong stock having a face edge longitudinally 70 grooved to form a blade-seat and a bifurcation at one end agreeing with said face groove, a blade-clamp and graduated limb pivoted to oscillate in said bifurcation adjacent to an index mark on said stock, a 75 blade adapted to be fastened in said clamp and oscillate therewith and swing to seat in said face groove, and the end of the stock opposite to the bifurcation V-forked to form a center-head in alinement with the seated 80 edge of the blade.

3. A combination tool, comprising a stock having a working edge-face and a bifurcation through said face, a blade-clamp pivoted in said bifurcation to oscillate in a plane 85 cutting said edge-face longitudinally and standing at right angles thereto crosswise, a blade adapted to be fastened in said clamp to oscillate edgewise therewith, and a releasable detent on said stock to limit the oscillation of said clamp and stop said blade 90 at a predetermined angle to said face.

4. A combination tool, comprising a stock having a face-edge and a longitudinal bifurcation through one end of said face-edge, an 95 oscillatory blade-clamp pivoted in said bifurcation, a blade adapted to be fastened in said clamp, a releasable detent to limit the oscillation of said clamp and stop the blade at right angles to said face-edge, and 100 a spirit-level fastened to said stock parallel with its face edge.

5. A combination tool, comprising a stock having a longitudinally-grooved face-edge, a bifurcation agreeing with said groove, a 105 blade-clamp pivoted in said bifurcation to oscillate in a plane agreeing with said groove, a blade adapted to be fastened in said clamp and oscillate edgewise therewith to seat said blade in said groove, a releasable detent on said stock to limit the oscillation of said clamp to stop the blade at a predetermined angle to said face-edge, a spirit 110 level fastened on said stock parallel with its face-edge, and the stock V-forked to form a center-head in alinement with the seated edge of said blade.

6. A combination tool, comprising a faced stock having a face blade-seat to support a blade parallel with said face and a back 120 blade-seat turned to 180 degrees from or reversed and parallel with said face blade-seat, a blade-clamp pivoted to said stock centrally between said blade-seats, a blade adapted to be fastened in said pivoted blade-clamp to oscillate therewith and swing to either seat, and a spirit-level mounted on said stock 125 parallel with the face and blade-seats thereof.

7. A combination tool, comprising a stock 130

- having a working edge and blade-seat parallel and faced in the same direction and a back blade-seat parallel with and faced oppositely to said working edge, an integral 5 blade-clamp and limb pivoted to said stock centrally between said blade-seats, a blade adapted to be fastened in said clamp and oscillate therewith to swing 180 degrees from one blade-seat to the other, and an index 10 to denote by the graduations on said limb the angle the blade bears to said working edge.
8. A combination tool, comprising a stock having a face-edge and a face blade-seat parallel 15 with said edge and a reverse back blade-seat parallel with said face blade-seat, a blade-clamp pivoted centrally between said blade-seats, a blade adapted to be fastened in said blade-clamp to oscillate therewith and 20 swing 180 degrees to either blade-seat, a quadrant limb having a graduated scale of ninety degrees and rigidly connected to oscillate with said blade-clamp, and two index 25 marks disposed ninety degrees apart on said stock to denote all angles of the blade within the range of its swing.
9. A combination tool, comprising a faced stock having a blade-seat faced in the same direction and parallel with the face of the 30 stock and a back blade-seat faced oppositely and parallel therewith, a rigidly connected blade-clamp and graduated limb pivoted to the stock centrally between said blade-seats, a blade adapted to be fastened rigidly in 35 said blade-clamp and oscillate therewith 180 degrees to swing said blade to either of said opposite blade-seats, an index-mark to denote on said graduated limb the angle the blade bears to the face of the stock, and a spirit-level disposed and fastened to said 40 stock parallel with its face.
10. A combination tool, comprising an oblong stock having an edge-face grooved longitudinally to form a blade-seat and a parallel back blade-seat faced oppositely to 45 said face blade-seat, a blade adapted to be rigidly fastened in an oscillatory blade-clamp, an oscillatory blade-clamp and rigidly connected limb pivoted in a bifurcation 50 at one end of said stock to oscillate and swing said blade in a plane agreeing with the blade-seats and throughout an arc of 180 degrees between said blade-seats, the opposite end of the stock forked 55 to form a center-head in alinement with the edge of the seated blade, an index-mark on the stock to denote by the graduations of the limb the angle that the blade bears to the face of said stock, and a spirit-level disposed and fastened parallel with said face.
- 60 11. A combination tool, comprising a bifurcated stock, a blade, an oscillatory blade-clamp having a hub pivoted between the branches of said bifurcation, a pivot bolt disposed through said branches and hub and having a threaded head seated in one branch an intermediate tapered part fitted in the hub and a threaded end to receive a tightening-nut against the outside of the other branch.
12. A combination tool, comprising a stock, a blade having a longitudinal groove, an oscillatory blade-clamp pivoted to said stock, said clamp bifurcated to form a blade-seat, a clamping-bolt cased centrally beneath said blade-seat and having an extension with a lip to engage the groove in said blade, a radially projecting pin on said bolt, and diametrically opposite chambers in the bolt-casing to receive said radial pin at either of the opposite sides whereby said lipped extension is shiftable to opposite sides of the blade-seat.
13. A combination tool, comprising a faced stock, a swinging blade pivoted to said stock, an adjustable releasable detent to stop the blade at a predetermined angle to the face of said stock and adapted to be set released to allow the blade to swing by said predetermined angle both ways unobstructed and adapted to be adjusted to exactly stop said blade at said predetermined angle when set therefor.
14. A combination tool, comprising a faced stock, an oscillatory blade-clamp pivoted to said stock, a detent pivoted to said stock to revolve through the path of an arm of said blade-clamp to stop its oscillation at a predetermined angle and a radial notch in said detent adapted to be turned to agree with the path of said arm and allow the blade-clamp to oscillate unobstructed.
15. A combination tool, comprising a faced stock, an oscillatory blade-clamp pivoted to said stock, a headed journal screwed into said stock, a detent mounted on said journal to revolve across the path of said blade-clamp to stop it at a predetermined angle, said journal adapted to be turned to screw it farther into or out of said stock to change the position of said detent to adjust the stopping point of said blade-clamp.
16. A combination tool, comprising a faced stock, an oscillatory blade-clamp pivoted to said stock, a longitudinally adjustable headed journal projected from said stock, a detent mounted on said journal to revolve across the path of oscillation of said blade-clamp, and a spring interposed between the stock and detent to retain the detent against the head of said journal.
17. The adjustable releasable detent, comprising a headed journal having a threaded point disposed to turn in a supporting seat and adjust the distance between said head and seat, a revoluble detent mounted on said journal against its head and disposed to swing across and in and out of the path of an element to be stopped and released, and

a spring interposed between said detent and said seat to retain said detent against the head of said journal.

18. The reversible blade-clamp, comprising a body shaped to form a blade-seat, a clamping bolt cased centrally beneath said blade-seat and having an extension with a lip adapted to engage a longitudinal groove in the side of a blade disposed in said blade-seat, a radially projecting pin on said clamp-

ing-bolt, and diametrically opposite chambers in the bolt-casing to receive said radial pin in either chamber.

In testimony whereof I affix my signature in presence of two witnesses.

EMANUEL OEHRLÉ.
